LUGGAGE BAG

Leonard George Arpin, Fort Lauderdale, Fla., assignor of one-half to Howard C. Jelks, Fort Lauderdale, Fla.

Application May 28, 1933, Serial No. 671,977

6 Claims. (CL 190—43)

This invention relates to a luggage bag and concerns itself with a structure primarily adapted for traveling in vehicles such as automobiles or the like.

5 A luggage bag for vehicle travel should possess the following characteristics: it must be easy to pack without wrinkling the clothes; it should also be of such a nature that it can be quickly unpacked and wherein an article of clothing may 10 be removed without disturbing the others. It should also be of such a character that it can contain both men's and women's clothes. Besides it should be dust proof and water proof 15 and of such a practical nature that it can be readily suspended from one of the inner sides of the vehicle or placed upon the back seat when such seat is not in use. To this end such a luggage bag requires certain flexibility so that it can adapt itself to different positions without 20 wrinkling or improperly creasing the clothes.

The invention comprises the novel structure and combination of parts hereinafter described and more particularly pointed out and defined in the appended claims.

25 In the accompanying drawing which illustrates a preferred form of this invention and in which similar reference numerals refer to similar features in the different views:

Figure 1 is an end elevational view of a luggage 30 bag involving this invention.

Figure 2 is an enlarged side elevational view of the bag with parts broken away.

Figure 3 is an enlarged sectional view taken upon the line III—III of Figure 2 looking in the 35 direction of the arrow.

Figure 4 is an enlarged fragmentary sectional view showing a portion of the interior of the bag.

Figure 5 is an enlarged fragmentary sectional view of the bag taken at right angles to the view 40 of Figure 4.

In the illustrated embodiment of this invention, the luggage bag is constructed from a pair of flexible side portions 1 and 2 which may consist of canvas, leather or any suitable fabric. 45 These side pieces are connected by an intermediate portion 3 which is fastened to the side portions by means of folded leather strips 4 or the like as shown in Figure 3. The intermediate portion is slotted for access to the bag as indicated at 5. In the present instance the slotted portion extends over the top of the bag and substantially halfway down the sides thereof. An arcuate metal plate 6 is preferably secured to the upper portion of the bag by means of rivets 50 or the like and the slotted portion of the bag

which fits over the metal plate 6 may be closed by a hookless fastener 7 or by any other suitable means. A bracket 8 is attached to the metal plate 6 for supporting clothes hook hangers or the like from which pants and coats may be suspended. The lower edges of the plate 6 are provided with keepers or guideways 9 in which the ends of suitable rods 10 are confined. These rods 10 can readily be removed or can be slid in the guideways as desired. The metal rods 10 are 10 preferably designed to support a lady's dress which may be folded thereover or suspended therefrom.

In the drawing, a man's suit 11 is shown suspended from the bracket 8 by means of an ordinary clothes hanger and a woman's garments 12 are shown supported from the wires 10. In order to carry shirts or similar articles a pair of pockets 13 and 14 are provided adjacent the side 1 of the bag as shown in Figure 3. The upper 20 ends of these pockets are adapted to be closed by snap fasteners 15 or the like. In the drawing wearing apparel 16 is shown within the pockets.

A handle 17 is adapted to be attached to the upper surface of the bag for the purpose of carrying the same or supporting the same from a hook upon the sides of a motor vehicle as shown in Figure 1. It will however be appreciated that due to the flexible character of the bag, it may be readily folded without materially wrinkling 25 the garments or it may be positioned upon the floor of the car and inclined against the rear seat in the event that the rear seat is not required for two passengers. The material from which the bag is made is preferably water proof 30 and the bag as constructed is also dust proof. 35 As a result the bag lends itself to the conveniences of vehicle travel.

It will readily be appreciated that by opening the hookless fastener 7 the side of the bag designated by the reference numeral 2 may be folded downwardly making it very easy to pack the bag with garments. For the same reason, it will be evident that garments may be readily removed 40 from the bag without disturbing those garments that it is desired to have remain in the bag.

The bottom of the bag may also be provided with a handle 17a if desired. This facilitates carrying the bag, since under certain conditions the bag may be folded at its mid-section and the handles brought together which obviously 45 reduces the length as so carried.

I am aware that many changes may be made and numerous details of construction may be varied through a wide range without departing 50 55

from the principles of this invention, and I, therefore, do not purpose limiting the patent granted hereon otherwise than necessitated by the appended claims.

5 I claim as my invention:

1. A luggage bag comprising flexible side members and an intermediate flexible web connecting said side members and forming the top, bottom and side edges of said bag, a curved metal plate in the top portion of the bag, said web having an entrance slit extending over said metal plate, hookless fasteners for closing said slit, a handle secured to the top portion of said bag, a second handle secured to the bottom portion of said bag, said bag being adapted to be folded at mid-section and the handles brought together for carrying the same.

10 2. A luggage bag comprising flexible side members and an intermediate flexible web between said side members and forming the top, bottom and side edges of the bag, means for reinforcing the top portion of said web, said web having an entrance slit extending over the top portion thereof, a handle at the top of said bag and a handle at the bottom of said bag, said bag being adapted to be folded at mid-section and said handles brought together for carrying the same.

15 3. A luggage bag comprising flexible side members, an intermediate web having outwardly directed marginal flanges secured to the edges of said side members and forming the top, bottom and side edges of said bag, means for reinforcing the top portion of said web, a handle secured to the top portion of said bag and a handle secured

to the bottom portion of said bag, said bag being adapted to be folded at mid-section for bringing said handles together for carrying said bag.

4. A luggage bag comprising flexible side members, a flexible web connecting said side members and forming the top, bottom and side edges of said bag, a curved metal plate secured to the top portion of said web, said plate having parallel guideways formed thereon for receiving clothes supporting rods, said web having an entrance slit extending over said plate, a handle at the top of said bag and a handle at the bottom of said bag, said bag being adapted to be folded at mid-section for bringing said handles together.

10 5. A luggage bag comprising flexible side members and an intermediate flexible web between said side members, means forming a bead at the junctures of said web with said side portions, said bag having a top portion and a bottom portion, reinforcing means in the top portion, a handle at the top portion of the bag, a handle at the bottom portion of the bag, said bag being foldable at mid-section to bring said handles together for carrying said bag.

15 6. A closed luggage bag comprising flexible side portions and an intermediate web adapted for containing clothes in suspended relation, said bag having a handle at the top and a handle at the bottom and being adapted to be folded at substantially mid-section for forming a substantially U-shaped bag.

20 25 30 LEONARD GEORGE ARPIN.
